CLAIM

We claim the ornamental design for a television with rollable display screen, as shown and described.

DESCRIPTION

FIG. 1 is a front perspective view of a television with rollable display screen showing the new design;
FIG. 2 is a front elevation view thereof;
FIG. 3 is a rear elevation view thereof;
FIG. 4 is a left-side elevation view thereof;
FIG. 5 is a right-side elevation view thereof;
FIG. 6 is a top plan view thereof;
FIG. 7 is a bottom plan view thereof;
FIG. 8 is a rear perspective view with an enlarged detail view thereof;
FIG. 9 is a front perspective view of the television with rollable display screen of FIG. 1 shown with the display screen in a partially rolled up position;
FIG. 10 is a front elevation view thereof;
FIG. 11 is a rear elevation view thereof;
FIG. 12 is a left-side elevation view thereof;
FIG. 13 is a right-side elevation view thereof;
FIG. 14 is a top plan view thereof;
FIG. 15 is a bottom plan view thereof;
(Continued)

FIG. 16 is a front perspective view of the television with rollable display screen of FIG. 1 shown with the display screen in a fully rolled up position;
FIG. 17 is a front elevation view thereof;
FIG. 18 is a rear elevation view thereof;
FIG. 19 is a left-side elevation view thereof;
FIG. 20 is a right-side elevation view thereof;
FIG. 21 is a top plan view thereof; and,
FIG. 22 is a bottom plan view thereof. The broken lines represent portions of the television with rollable display screen that form no part of the claimed design.
